ENGINE SPEED GOVERNOR

August W. Kretschmar, Detroit, Mich.

Application September 27, 1940, Serial No. 358,676

10 Claims. (Cl. 267—1)

This invention relates generally to speed governors and more particularly to governors for controlling operation of carburetors of internal combustion engines.

It is an object of the present invention to provide a new and improved speed governor which is a unit separate from or external of the carburetor controlled thereby.

Another object of the invention is to provide a speed governor having a new and improved arrangement of the operating parts thereof for improved efficiency of operation.

A further object of the invention is to provide in a speed governor having a spring, opposing operation of the carburetor valve by engine-created suction, new and improved means carried by the spring for varying the force exerted thereby in accordance with variations in the force of engine-created suction.

Other objects of the invention will become apparent from the following detailed description taken in connection with the accompanying drawings, in which:

Figure 1 is a view shown in longitudinal central section of my improved speed governor;

Figure 2 is a cross-sectional view of the governor and part of a carburetor taken along the line and in the direction of the arrows 2—2 of Figure 1;

Figure 3 is a fragmentary sectional view taken along the line 3—3 of Figure 2 to show certain details of the manual means for controlling the carburetor throttle valve;

Figure 4 is a view in cross section of the speed governor and part of the carburetor taken along the line 4—4 of Figure 1;

Figure 5 is a view shown partly in section taken along the line 5—5 of Figure 2 to show certain details of the manual control means for the carburetor throttle valve; and

Figure 6 is a view similar to Figure 1 showing the operating parts of the speed governor in positions they will assume during idling operation of an engine.

Referring to the drawings by characters of reference, the numeral 10 designates in general the intake conduit of a carburetor, the conduit having at one end thereof the usual out-turned flange 11 to receive screws or other suitable means for rigidly securing the carburetor to the intake manifold of an internal combustion engine, not shown. Flow of fuel and air through the carburetor conduit 10 is controlled by a throttle or so-called butterfly valve 12 in the conduit 10, which valve is secured to and inter-

mediate the ends of a shaft 13 extending transversely through the side wall of the conduit 10. One end of the valve shaft 13 extends externally of the carburetor conduit 10 and projects into a casing 15 which may be integral with and joined to the carburetor conduit 10 by a hollow connecting conduit 14 or may be separate therefrom, as desired. The shaft 13 is preferably journaled in a roller bearing 16 mounted in the conduit 14 adjacent the casing 15. The casing 15 houses the operating and associated mechanism of the speed governor and comprises a top wall 17, bottom wall 18, end walls 19 and 20, a rear wall 21 and a front wall or removable cover 22.

The end of the shaft 13 which projects into the casing 15 is provided with a rotatable member or lever which is integral with the shaft to rotate therewith and is in the form of a segment of a drum 23 having its center of rotation coincident with the axis of rotation of the valve shaft 13. Secured to the periphery of the drum segment 23 is one end of a strap 24 which may be secured to the drum segment by a screw 25, the other end of the strap being attached to a movable wall 26 of a pressure responsive bellows member 27 which is disposed within the casing 15. The other end of the bellows 27 is sealed and secured around its periphery by an out-turned flange 27a of a fitting 28 which is rigidly secured to the casing end wall 19 by screws 29. The fitting 28 may be connected by a suitable conduit, not shown, to the intake manifold of the engine whose speed is to be controlled, with the result that the bellows 27 will expand and collapse in accordance with engine-created suction and will act upon decrease in pressure in the intake manifold to move the throttle valve 12 toward closed position or counter-clockwise, facing Figure 1.

Disposed within the casing 15 below the drum segment 23 there is a supporting member 30 for a leaf spring 31, which spring acts in opposition to the bellows 27 to move the throttle valve 12 toward open position. The supporting member 30 is of general rectangular form, and extending longitudinally within the casing 15 the supporting member is fulcrumed intermediate its ends on a shaft 32, one end of which is rigidly secured in and to the casing rear wall 21. As shown, on one side of the fulcrum 32 or beneath the bellows 27, the supporting member 30 is provided with a hollow rectangular end portion 33 integral with which the supporting member includes spaced, longitudinally extending, sub-

stantially parallel side members 34 having aligning apertures adjacent the inner end of the rectangular end portion 33 to receive the shaft 32. Adjacent the shaft 32, the supporting member end portion 33 is provided with integrated top and side walls to which is removably connected a bottom wall or plate 36 for providing a recess 35 therebetween having an opening 39 facing toward the opposite end of the supporting member 30. Extending into the recess 35, an end portion of the leaf spring 31 rests against the upper surface of the bottom wall or plate 36, and adjacent its end is clamped between the plate 36 and the member 33 by a screw 40. As shown in Figure 4, the width of the leaf spring 31 tapers down gradually from a maximum width, as at 52, intermediate its ends to an eyelet 41 which receives the screw 40. A bore 42 extending longitudinally through the supporting member portion 33 receives the shank 43 of a rotatable screw which has a threaded end portion 44 within the recess 35, and screwthreaded onto the screw there is an adjustment member 45 in the worm of a square nut for varying the effective length of the leaf spring 31. One side of the nut 45 slidably engages the lower surface of the top wall of the recess 35 while an opposite side of the nut slidably engages the upper surface of the leaf spring 31, these sides of the nut 45 preferably being rounded, as shown, to reduce friction between the parts. By rotating the screw, it will be seen that the nut 45 will move along the screw and that by moving the nut, for example, to the right, Figures 1 and 6, the effective length of the spring 31 is shortened with corresponding increase in resistance of the spring to flex.

The ends of the side members 34 are integrally joined together by a horizontal transverse wall 46, beneath which a rocker member 47 is carried by the free end of the leaf spring 31. From the maximum width, as at 52, of the leaf spring 31, the spring tapers down to a minimum width, as at 52a, adjacent the free end of the spring. As shown in Figures 1 and 6, the rocker member 47 is provided with a lower flat surface which seats on the upper surface of the leaf spring 31 and terminates substantially at the minimum width of the spring 31 and also the rocker member is provided with an upwardly facing convex rocker surface 48 having a center of the radius of curvature which is preferably substantially at the point designated 48a, the convex surface 48 engaging the lower surface of the transverse wall 46 to rock thereon. Also carried by the free end of the leaf spring 31 but on the underside thereof is a second rocker member 50 which is adapted to flex the spring 31 longitudinally thereof, and, in so doing, to increase the tension or resistance of the spring to flex by coming in contact with a wider part of the spring. This second rocker member 50 is of general rectangular shape, and adjacent one end is secured to and adjacent the free end of the spring 31 by a screw 51, which screw-threads onto the upper rocker member 47 and through an eyelet 53 on the free end of the spring, thus securing both rocker members to the spring 31. Where the rocker member 50 is attached by the screw 51 to the spring 31, an upper portion of the rocker member is provided with a flat surface as shown, which flat surface at substantially the point 48a or at the minimum width 52a of the spring, runs into a convex or rocker surface 54, preferably a segment of a cylinder for engaging the underside of the spring 31.

10 The other end of the rocker member 50 is disposed intermediate the ends of the spring 31 and is provided in its lower surface with a semi-cylindrical, transversely-extending recess in which a lower cross member of a rectangular link 55 is retained by a removable plate 56 which is secured to the rocker member 50 by screws 57. Similarly, the upper cross member of the link 55 is retained in a recess of the drum segment 23 by a removable retainer plate 60 which is secured to the drum segment by screws 61.

15 Within the casing 15 immediately above the transverse wall 46 of the supporting member 30 there is a block-like support 62 which is rigidly secured to the casing end wall 20 for supporting an adjustable member in the form of a thumb screw 63. The adjustment screw 63 screwthreads vertically through the block 62 and has its lower end engaging the upper surface of the transverse wall 46. It will be seen that by means of the adjustment screw 63 the supporting member 30 may be moved about its fulcrum or shaft 32 to adjust the tension of the spring 31. In order to ensure against upsetting of the adjustment of 20 the supporting member 30, a helical coil spring 25 64 may be provided, and surrounding the screw is held under compression between the supporting block 62 and the head of the screw.

25 Referring now more particularly to Figures 2 and 3, on the other side of the carburetor conduit 10 from the above described speed governor, the throttle valve shaft 13 projects externally of the conduit 10 and is journaled in a bearing 65 mounted in an external hollow boss 66 of the conduit 10. Rotatably mounted on the boss 66 is a tubular hub 67 of an operating lever 68, which hub is retained on the boss 66 by a retainer plate 69 engaging in an annular recess in the hub and rigidly secured to the conduit 10 by screws 70. Within the hollow boss 66, the valve shaft 13 is provided with a reduced end portion 70a on which a sleeve 71 is provided having a laterally extending lug 72, the sleeve 71 being secured to the shaft 13 to rotate therewith by means of a nut 73 screwthreaded onto the outer end of the reduced shaft portion 70a. Closing the outer end of the hub 67, a plate 74 is provided and secured to the hub by screws 75, the plate 74 having a lug 76 extending into 30 the boss 66 for engaging the lug 72 on the valve shaft 13. The operating lever 68 is to be connected to the engine accelerator pedal having the usual return spring, not shown, for returning the lever 68 to the engine idling position shown 35 in Figure 6.

Operation

40 When an internal combustion engine controlled by the herein described governor is idling, the throttle control lever 68 will be held by a throttle return spring usually connected to the accelerator pedal in the position shown in Figure 6, and lug 76 engaging the lug 72 will hold the throttle valve 12 in engine idling position. Because of the relatively low sub-atmospheric pressure in the intake manifold of an internal combustion engine during idling of the engine, the bellows 27 will be collapsed and through the strap 24 will act to rotate the drum segment 23 in a counterclockwise direction facing Figures 1 or 6 and thus will aid in holding the throttle valve 12 in a near closed position against the opposition of the spring 31. As the throttle valve is moved toward closed position, the drum segment 23, through the connecting link 55, pulls the lower

end of the rocker member 50 upward, during which movement the spring 31 is flexed longitudinally thereof, and the rocker member 47 rocks on the under-surface of the wall 46. It will be seen that as the member 50 rocks it moves from its point of contact at the narrowest point of the spring toward the widest point thus meeting increased resistance of the spring. The rocking action of the rocking member 47 causes the free end of the spring 31 to be bent downwardly while at the same time the lower rocker member 50 rocks against the underside of the spring 31 longitudinally thereof. As more of the rocker surface 54 comes in contact with the lower surface of the spring 31, it will be seen that the resistance or tension of the spring is increased, causing the spring to take substantially the form shown in Figure 6. The spring 31 acts to open the throttle valve 12, and the position to which the valve will be opened and consequently the high limit speed at which the engine will be permitted to operate may be regulated by the adjustment screw 63. For example, it will be seen that when the adjustment screw 63 is rotated to move downwardly, the spring 31 will be flexed and, since the end of the rocker member 50 which is connected to the link 55 will not move with movement of the support 30, the result is that the spring 31 will be placed under additional tension and consequently will be adapted to correspondingly move 30 the valve 12 further toward open position. When the accelerator-operated lever 68 is moved clockwise facing Figures 1 or 6, the lug 72 carried by the valve shaft 13 follows the lug 16 under action of the spring 31. As the spring 31 tends to return to the position shown in Figure 1 or to straighten out, rocker member 47 rocks on the under surface of the wall 46, permitting the free end of the spring to move upwardly, while at the same time the contact surface 54 of the lower 40 rocker member 50 moves away from the underside of the spring 31. This movement of the rocker member 50 in effect elongates the effective length of the spring 31, and in so doing moves from the widest part of the spring toward the narrowest part with corresponding decrease in resistance of the spring, with the result that the spring tension decreases and is overcome by the engine-created suction acting on the bellows 27. This results in a balanced condition between the bellows 27 and the force of spring 31 which limits the open position of the valve to the desired position, determined, as previously mentioned, by means of the adjustment screw 63. The rate at which the force of the spring 31 changes as the 45 rocker members 47 and 50 rock is determined partly by the tapers of the spring and partly by changing of the effective length of the spring.

While I have shown and described my invention in detail it is to be understood that the same is to be limited only by the appended claims for many changes may be made without departing from the spirit and scope of the invention.

What I claim is:

1. A device for resisting movement of an element comprising an elongated spring anchored at one of its ends against flexing thereof and having a portion adjacent its opposite end tapered toward said last mentioned end, a pair of rocker members secured to opposite sides of said spring at said second mentioned spring end, one of said members extending from its respective spring side into operative connection with said element and being formed with a rocking surface tangent to said respective spring side at approximately

10 the apex of said tapered spring portion, the other of said members extending from its respective spring side and also being formed with a rocking surface, and means providing a surface upon which said second-mentioned rocking surface is rockable.

2. A device for resisting movement of an element comprising an elongated spring anchored at one of its ends and having a portion adjacent its opposite end tapered toward said last-mentioned end, means selectively movable between said spring ends for varying the effective spring length, a pair of rocker members secured to opposite sides of said spring at said second-mentioned spring end, one of said members extending from its respective spring side into operative connection with said element and being formed with a rocking surface tangent to said respective spring side at approximately the apex of said tapered spring portion, the other of said members extending from its respective spring side and also being formed with a rocking surface, and means providing a surface upon which said second-mentioned rocking surface is rockable.

3. A device for resisting movement of an element comprising an elongated spring anchored at one of its ends against flexing thereof and having a portion adjacent its opposite end tapered toward said last-mentioned end, a pair of rocker members secured to opposite sides of said spring at said second-mentioned spring end, one of said members extending from its respective spring side into operative connection with said element and being formed with a rocking surface tangent to said respective spring side at approximately the apex of said tapered spring portion, the other of said members extending from its respective spring side and also being formed with a rocking surface, means providing a surface upon which said second-mentioned rocking surface is rockable, and means selectively operable for varying the position of said next to the last mentioned surface.

4. A device for resisting movement of an element comprising an elongated spring anchored at one of its ends and having a portion adjacent its opposite end tapered toward said last-mentioned end, means selectively movable between said spring ends for varying the effective spring length, a pair of rocker members secured to opposite sides of said spring at said second-mentioned spring end, one of said members extending from its respective spring side into operative connection with said element and being formed with a rocking surface tangent to said respective spring side at approximately the apex of said tapered spring portion, the other of said members extending from its respective spring side and also being formed with a rocking surface, means providing a surface upon which said second-mentioned rocking surface is rockable, and means selectively operable for varying the position of said next to the last mentioned surface.

5. A device for resisting movement of an element comprising an elongated spring anchored at one of its ends against flexing thereof and having a portion adjacent its opposite end tapered toward said last-mentioned end, a pair of rocker members secured to opposite sides of said spring at said second mentioned spring end and extending laterally therefrom, the outer end of one of said members being in operative connection with said element and formed with a rocking surface tangent to said respective spring side at approx-

imately the apex of said tapered spring portion, the outer end of the other of said members also being formed with a rocking surface, and means providing a surface upon which said second-mentioned rocking surface is rockable.

6. A device for resisting movement of an element comprising an elongated spring anchored at one of its ends against flexing thereat and having a portion adjacent its opposite end tapered toward said last mentioned end, a pair of rocker members secured to opposite sides of said spring at said second-mentioned spring end, one of said members extending from its respective spring side into operative connection with said element and being formed with a rocking surface the center of curvature of which establishes tangency between said surface and said last-mentioned spring side at approximately the apex of said tapered spring portion during spring inactivity, the other of said members extending from its respective spring side and being formed with a rocking surface the center of curvature of which resides approximately at said apex, and means providing a surface upon which said second-mentioned rocking surface is rockable.

7. A device for resisting movement of an element comprising an elongated, normally flat spring anchored at one of its ends against flexing thereat and having a portion adjacent its opposite end tapered toward said last-mentioned end, a pair of rocker members each having a flat surface secured to one of the two opposite sides of said spring and extending from said second-mentioned spring end to the apex of said tapered spring portion, one of said members extending laterally outwardly from its respective spring side into operative connection with said element and being formed with a rocking surface tangent to the inner end of its respective flat surface and curved away from said respective spring side and in the general direction of said first-mentioned spring end, the other of said members extending laterally outwardly between the ends of its respective flat surface and being formed at its outer end with a rocking surface, and means providing a surface upon which said second-mentioned rocking surface is rockable.

8. A device for resisting movement of an element comprising an elongated, normally flat spring anchored at one of its ends against flexing thereat and having a portion adjacent its opposite end tapered toward said last-mentioned end, a pair of rocker members each having a flat surface secured to one of the two opposite sides of said spring and extending from said second-mentioned spring end to the apex of said tapered spring portion, one of said members extending laterally outwardly from its respective spring side into operative connection with said element and being formed with a rocking surface tangent to the inner end of its respective flat surface and curved away from said respective

spring side and in the general direction of said first-mentioned spring end, the other of said members extending laterally outwardly between the ends of its respective flat surface and being formed at its outer end with a rocking surface, and means providing a surface upon which said second-mentioned rocking surface is rockable, said first-mentioned rocking surface having a center of curvature laterally spaced from said first mentioned spring side and said second mentioned rocking surface having a center of curvature residing substantially at said apex.

9. A device for resisting movement of an element comprising an elongated, normally flat spring anchored at one of its ends and having a portion adjacent its opposite end tapered toward said last-mentioned end, means operable for selectively varying the effective length of said spring, a pair of rocker members each having a flat surface secured to one of the two opposite sides of said spring and extending from said second-mentioned spring end to the apex of said tapered spring portion, one of said members extending laterally outwardly from its respective spring side into operative connection with said element and being formed with a rocking surface tangent to the inner end of its respective flat surface and curved away from said respective spring side and in the general direction of said first-mentioned spring end, the other of said members extending laterally outwardly between the ends of its respective flat surface and being formed at its outer end with a rocking surface, means providing a surface upon which said second-mentioned rocking surface is rockable, and means operable for selectively varying the position of the next to the last mentioned surface.

10. A device for resisting movement of an element comprising an elongated, normally flat spring tapered in opposite directions along its length so as to have a portion intermediate its two ends of greatest width and a portion adjacent each of said ends of least width, said spring being anchored at one of said ends against flexing thereat, a pair of rocker members each having a flat surface secured to one of the two opposite sides of said spring and extending from the other of said spring ends to said position of least width thereadjacent, one of said members extending laterally outwardly from its respective spring side into operative connection with said element and being formed with a rocking surface tangent to the inner end of its respective flat surface and curved away from said respective spring side and in the general direction of said one spring end, the other of said members extending laterally outwardly between the ends of its respective flat surface and being formed at its outer end with a rocking surface, and means providing a surface upon which said second-mentioned rocking surface is rockable.

AUGUST W. KRETZSCHMAR.
